SCISSORS

John Albert Radford, Ashford, England, assignor to
Wilkinson Sword Limited, London, England, a British
company

Filed May 23, 1963, Ser. No. 75,029

Claims priority, application Great Britain Mar. 30, 1963

Term of patent 14 years

(Cl. D22—5)

Fig. 1.

Fig. 2.

Fig. 3.

Fig. 4.

Fig. 5.

FIGURE 1 is a bottom plan view showing my new design;

FIGURE 2 is a plan view of the opposite side to that seen in FIGURE 1;

FIGURE 3 is an elevation of the scissors as seen from the left hand side of FIGURE 2;

FIGURE 4 is an elevation of the scissors seen from the opposite side to FIGURE 3; and

FIGURE 5 is a fragmentary plan view thereof as it appears with the blades in the open position.

I claim:

The ornamental design for scissors, as shown.
